UNITED STATES PATENT OFFICE.

HENRY I. BENEDICT, OF NEW ORLEANS, LOUISIANA.

JACK.

1,324,721.

Specification of Letters Patent.

Patented Dec. 9, 1919.

Application filed March 14, 1918, Serial No. 222,327. Renewed May 29, 1919. Serial No. 300,789.

To all whom it may concern:

Be it known that I, HENRY I. BENEDICT, a citizen of the United States, and a resident of New Orleans, in the parish of Orleans 5 and State of Louisiana, have invented a new and Improved Jack, of which the following is a full, clear, and exact description.

This invention relates to lifting jacks for automobile and other uses, and the invention 10 has for its general objects to improve the construction and operation of devices of this character so as to be reliable and efficient in use, easily and quickly adjusted and of durable and substantial design.

15 A more specific object of the invention is the provision of a jack in which the lifting element is capable of being easily and quickly set to any desired position with respect to the load, and then operated by a 20 crank or equivalent means for lifting the load, the lifting element being in the form of a rack or toothed element with which meshes a worm wheel that is adapted to mesh with an operating worm, the worm 25 wheel being shiftable into and out of engagement with the worm, so that the lifting element can be readily adjusted to any desired position.

Another specific object of the invention is 30 the provision of a novel form of base and barrel adjustably mounted therein, whereby the height of the jack can be varied within comparatively wide limits, so that the jack is adaptable for high or low axles or other 35 loads.

With such objects in view, and others which will appear as the description proceeds, the invention comprises various novel features of construction and arrangement 40 of parts which will be set forth with particularity in the following description and claims appended hereto.

In the accompanying drawing, which 45 illustrates one embodiment of the invention and wherein similar characters of reference indicate corresponding parts in all the views,

Figure 1 is a central vertical section of the jack;

50 Figs. 2 and 3 are sectional views, respectively, on the lines 2-2 and 3-3, Fig. 1.

Referring to the drawing, A designates the base of the jack, B the barrel, C the lifting element, D the worm wheel meshing 55 with the lifting element, E the operating worm and F the releaser for throwing the

worm wheel into and out of engagement with the worm. The base A comprises a vertically disposed tubular body 1 having a bottom flange 2 to provide a suitable supporting surface for the jack, and in the upper end of the body 1 is an internal flange 3 which has at spaced points recesses 4, as shown in Fig. 3. The barrel B is of such diameter as to slide in the flange 3, and it 60 has a plurality of lugs 5 which are vertically spaced apart, these lugs being capable of sliding vertically through the recesses 4 of the base. By moving the barrel up or down while the lugs 5 are in alignment with the recesses 4, the effective height of the jack can be varied, and when the desired height is attained the barrel B is turned 65 with respect to the base to throw the lugs 5 out of alignment with the recesses 4, as 70 shown in Fig. 3. To hold the barrel in place in this position the upper part of the base is rendered resilient by reason of a vertical slit 6, at which slit are lugs 7 through which passes a clamping bolt 8 so as to contract the 75 upper end of the base and clamp it to the barrel B. To prevent the barrel from being entirely withdrawn from the base it is provided with an enlargement or flange 9 at its 80 lower end so as to interlock with the internal flange 3 of the base. 85

The lifting element C is preferably in the form of a screw and slides up and down in the barrel B, which has an opening 10 at its top through which the lifting element 90 projects, there being a load-carrying plate 11 on the upper end of the lifting element. The threads simply serve as teeth with which the worm wheel D permanently meshes. This worm wheel D is housed with- 95 in a chambered lateral extension 12 on the barrel, in which extension is also housed and rotatably mounted the worm E. On the worm is a shaft extension 13 having a non-circular end 14 to which an operating crank 100 may be applied for turning the worm. The worm wheel is mounted above the said worm so as to rest thereon by gravity, and as the worm is inclined to the horizontal the worm wheel tends by gravity to wedge into en- 105 gagement with both the lifting element C and the worm wheel. In order to permit of quick raising of the lifting element without the turning of the worm E, the worm wheel D is mounted in the releasing de- 110 vice F, which is a carrier in the form of a lever mounted to swing on a fulcrum 15,

said lever having an operating end 16 projecting out of the housing 12 so that, by pressing this handle 16 downwardly, as shown by dotted lines, the worm wheel is 5 raised out of engagement with the worm, so as to permit the lifting element C to be raised quickly into engagement with the load. When thus adjusted the handle 16 is released so that the worm wheel will engage 10 with the worm and thereby lock the lifting element in raised position. By now turning the worm E the worm wheel will transmit an up or down motion to the lifting element.

15 From the foregoing description taken in connection with the accompanying drawing, the advantages of the construction and method of operation will be readily understood by those skilled in the art to which the 20 invention appertains, and while I have described the principle of operation, together with the device which I now consider to be the best embodiment thereof, I desire to have it understood that the device shown 25 is merely illustrative and that such changes may be made when desired as fall within the scope of the appended claims.

Having thus described my invention, I claim as new and desire to secure by Letters Patent:

1. A jack comprising a casing having an opening, a lifting screw loosely positioned in said opening, a worm wheel meshing with the threads of said screw, a worm meshing

with said worm wheel, means for rotating 35 said worm, and means for moving the worm wheel out of mesh with said worm whereby the lifting screw may be moved in and out of said casing without operating said worm.

2. A jack comprising a casing, a lifting 40 screw loosely mounted in said casing, said lifting screw being rotatable, a worm, a worm wheel normally meshing with said worm and with said lifting screw, and a pivotally mounted supporting lever supporting said worm wheel, said lever being positioned to move the worm wheel out of engagement with said worm whereby the lifting screw may be moved independently 45 of the worm.

3. In a jack comprising a casing, a lifting screw loosely mounted in said casing, said lifting screw being rotatable, a driving worm, and a worm wheel meshing with the driving worm and the screw. 50

4. A jack comprising a supporting structure, a rotatable lifting element having threads, a rotary member having a single set of teeth engaging said threads whereby the rotation of the rotary member will move the 60 lifting element axially, a second member having threads engaging the teeth of the rotary member to rotate the rotary member, and means for relatively moving said members to disengage the same for permitting 65 said lifting element to move axially independently in either of two directions.

HENRY I. BENEDICT.
